UNITED STATES PATENT OFFICE

FRED A. OSTWALD, OF LOS ANGELES, CALIFORNIA

DESIGN FOR A DISPENSER FOR LIQUIDS

Application filed August 11, 1932. Serial No. 44,578. Term of patent 3½ years.

To all whom it may concern:

Be it known that I, FRED A. OSTWALD, a citizen of the United States, residing at Los Angeles, in the county of Los Angeles and State of California, have invented a new, original, and ornamental Design for a Dispenser for Liquids, of which the following is a specification, reference being had to the accompanying drawing, forming a part thereof.

Figure 1 is a front elevational view of a dispenser for liquids, showing my new design. the hood below the outlet being shown in open position.

Fig. 2 is a side elevational view of the same with the hood in closed position.

Fig. 3 is a view looking down from the top of Fig. 1, with the hood open.

I claim:

The ornamental design for a dispenser for liquids, as shown.

Signed at Los Angeles, in the county of Los Angeles, and State of California, this 5th day of August, 1932.

FRED A. OSTWALD.
